LIQUEFACTION OF CHLORINE

Dwight R. Means, Wadsworth, Ohio, assignor to
 Pittsburgh Plate Glass Company, Allegheny
 County, Pa., a corporation of Pennsylvania

Application October 5, 1940, Serial No. 359,915

5 Claims. (Cl. 62—175.5)

This invention relates to a method of condensing gaseous chlorine. In the usual methods of condensing chlorine, it is often observed that the cooling surface within the condenser becomes coated with a layer of waxy substance to such a degree that the heat transfer capacity of the equipment is greatly reduced. Accordingly, it has been found that such condensers require cleaning at regular intervals. The exact composition of the waxy deposit has not been determined, but it appears that such deposits are due to the presence of certain organic impurities, generally chlorinated compounds such as hexachloroethane, polychlorobenzene or other chlorohydrocarbons which often occur in gaseous electrolytic chlorine. These impurities are present in low concentration, generally below about 1 percent by weight.

In accordance with the present invention, I have been able to avoid the formation of this objectionable deposit, and thus, to obtain a more efficient operation of the chlorine condensers, I have found that formation of this deposit may be minimized or substantially eliminated by bathing or washing the cooling surfaces of the condenser with liquid chlorine. This may be done, for example, by causing a stream of liquid chlorine to flow along the cooling surfaces of the condenser. Alternatively, the cooling surfaces may be immersed in a pool of liquid chlorine.

The invention will be more fully understood by reference to the accompanying drawings, in which,

Fig. 1 is a diagrammatic sectional view of a preferred modification of my invention, and

Fig. 2 is a flow diagram which diagrammatically illustrates a further modification of the invention.

In accordance with the invention, as illustrated in Fig. 1, the condenser 1, is provided with cooling coils 7, an inlet for chlorine 8, outlets for withdrawing chlorine 6, and liquid chlorine 10. The device is also provided with a suitable manhole 9.

In the operation of the device, the condenser is filled approximately to the level of the liquid chlorine outlet with liquid chlorine. Thereafter, gaseous chlorine is introduced through inlet 8, underneath baffle 2, and is allowed to pass in contact with the cooling coils 7, whereby at least a portion of the chlorine is condensed, liquid chlorine is withdrawn from time to time through outlet 10, and uncondensed chlorine is withdrawn through outlet 6 for further condensation opera-

tions. By maintaining a pool of liquid chlorine of substantial depth in which all or a portion of the cooling coils are immersed, the formation of a waxy deposit upon the surfaces thereof is thereby prevented. If desired, this pool may be maintained in contact with the entire cooling surface throughout the cooling operations. On the other hand, however, this may be unnecessary since the chlorine may be cooled and condensed without utilization of the large pool of liquid chlorine and the waxy deposit removed from the surfaces periodically by raising the level of the liquid chlorine sufficiently high to immerse the coated cooling coils and thereby to remove the deposit. 15 Thus, while in the present modification, the liquid chlorine outlet is shown to be above the cooling level, it should be understood that this outlet may be placed at the bottom of the condenser, if desired.

20 The liquid chlorine withdrawn from outlet 10 will usually contain a substantial portion of the impurities which have been removed from the deposit or from the incoming gaseous chlorine. This chlorine may be used as such or, if desired, 25 may be revaporized to leave the waxy impurities in the solid state and the vaporized chlorine may thereafter be condensed in a substantially pure form by any convenient method. The uncondensed chlorine leaving the condenser is found 30 to be in a highly purified state and may be condensed by conventional methods. In the usual practice, the temperature maintained within the condenser is -10° C. The gaseous chlorine is introduced under a pressure of 35 lbs. per sq. in. 35 gage and at a temperature of 40° C.

In accordance with the modification diagrammatically illustrated in Fig. 2, I may provide a suitable cooling condenser with heat exchanger 12, having the usual brine inlets and outlets 13 40 and 14 respectively, and chlorine inlets and outlets 15 and 16 respectively. In order to prevent formation of a deposit upon the surfaces of the heat exchanger, a quantity of chlorine is introduced at 17, with gaseous chlorine to be cooled 45 and condensed, whereby a stream of liquid chlorine is caused to flow along a large portion of the cooling surface of the interchanger and is withdrawn with the uncondensed chlorine and liquid chlorine condensed during treatment at 16. 50 The condensed chlorine and uncondensed gaseous chlorine at 16 is introduced into separator 11, wherein gaseous and liquid chlorine are separated. The uncondensed gaseous chlorine is then introduced into a separate condenser through conduit 18, and liquid chlorine is with-

drawn as shown, a portion of the liquid chlorine being recycled through conduit 17, to the heat exchanger.

Although the present invention has been described with particular reference to specific details of certain embodiments thereof, it is not intended that such details shall be regarded as limitations upon the scope of the invention, except insofar as included in the accompanying claims.

I claim:

1. A method of cooling impure chlorine containing organic impurities which comprises cooling gaseous chlorine through a heat transfer wall at a pressure sufficiently high to insure liquification of at least a portion of the chlorine and bathing the cooling surface of the wall with liquid chlorine in addition to chlorine which may be condensed upon such surface to prevent accumulation of a waxy deposit upon the surface and recovering cooled gaseous and purified chlorine.

2. A method of treating impure chlorine containing an organic impurity which comprises introducing impure chlorine into a pool of liquid chlorine, cooling the pool by heat transfer through a cooling surface while bathing the cooling surface with said liquid chlorine to prevent accumulation of a waxy deposit upon the surface and

removing purified gaseous chlorine from the pool.

3. A method of treating impure chlorine containing an organic impurity which comprises introducing impure chlorine into a pool of liquid chlorine, cooling the pool by heat transfer through a cooling surface while bathing the cooling surface with said liquid chlorine to prevent accumulation of a waxy deposit upon the surface and removing purified gaseous chlorine from the pool and withdrawing impure liquid chlorine from the pool.

4. A method of treating impure gaseous chlorine containing an organic impurity which comprises introducing impure gaseous chlorine beneath the surface of a pool of liquid chlorine, cooling the pool by heat transfer through a cooling surface while bathing the cooling surface with said liquid chlorine to prevent accumulation of a waxy deposit upon the surface and removing purified gaseous chlorine from the pool.

5. A method which comprises cooling gaseous chlorine containing an organic impurity by heat transfer through a cooling surface, washing said surface with liquid chlorine in addition to chlorine which may be condensed upon such surface whereby accumulation of waxy deposits on said surface is prevented and recovering the cooled gaseous chlorine.
